UNITED STATES PATENT OFFICE

2,154,593

CRANKCASE VENTILATING SYSTEM

Gilbert Way, Detroit, Mich., assignor to Chrysler Corporation, Highland Park, Mich., a corporation of Delaware

Application November 3, 1937, Serial No. 172,515

3 Claims. (Cl. 123—119)

This invention relates to improvements in internal combustion engines.

More particularly, the invention pertains to improved internal combustion engine crank case ventilation.

One of the main objects of the invention is the provision of means for circulating through the crank case of an internal combustion engine, a current of fresh air which is sufficient in quantity to remove crank case lubricant diluents, such as products of combustion, water of condensation and fuel, during idling operation, and which is augmented during intermediate and high speed operations of the engine sufficiently to accomplish this result while also compensate for the introduction of the blow-by gases into the crank case during such engine operation.

Another object of the invention is the provision of improved means for applying manifold suction to and automatically controlling the application thereof on the crank case of an internal combustion engine in order to maintain a desired flow of fresh air through the crank case during that fluctuation of the manifold suction which normally occurs, for example, in the operation of a motor vehicle.

Further objects of the invention are to provide improved valve means in a passage leading from the crank case to the fuel mixture system of an internal combustion engine for controlling the quantity of ventilating air flowing through the crank case; to provide valve means of this character which is operable in such timed relation with respect to the carburetor throttle valve of the engine as to compensate for manifold vacuum variations which result from variations of the throttle valve; to provide an improved vacuum controlled valve construction which enables the throttle valve shaft of the carburetor to be used as a valve member of the ventilating system.

An additional object of the invention is the provision of means for rendering the ventilation system inoperative and preventing the introduction of air and crank case diluents into the fuel mixture system of the engine during starting operation.

An illustrated embodiment of the invention is shown in the accompanying drawing, in which:

Fig. 1 is a transverse vertical sectional view of an internal combustion engine which is equipped with the improved crank case ventilating system.

Fig. 2 is an enlarged, fragmentary vertical sectional view taken on the line 2—2 of Fig. 1.

Fig. 3 is a fragmentary, mainly vertical, sectional view taken on the line 3—3 of Fig. 2.

Fig. 4 is a fragmentary sectional view, similar to Fig. 3 but showing the parts of the structure in a changed position.

In the drawing is illustrated an embodiment of the improved crank case ventilating system in an internal combustion engine, generally designated by the numeral 10, of the type conventionally used in automotive vehicles. The engine 10 comprises a crank case 11, cylinders 12 having pistons 13 therein and a fuel induction system which includes inlet ports 14 and an inlet manifold, generally designated by the numeral 15. Mounted on the inlet manifold 15 is a carburetor 16 having a body portion 16' in which is provided a fuel mixture passage 17 which communicates with the interior of the intake manifold. An oil filler sprout 18 is mounted on the side of the crank case 11 and provided with an open upper extremity through which air under atmospheric pressure is admitted to the interior of the crank case. Formed in the side of the engine opposite that on which the oil filler sprout 18 is located, is a valve chamber 19 which is communicatively connected with the crank case by a passage 20. The valve chamber 19 is provided with a removable closure 21 having an aperture therein through which a conduit 22 extends. The lower end of the conduit 22, as viewed in Fig. 1, communicates with the interior of the valve chamber 19 and with the interior of the crank case through the passage 20. The upper end of the conduit 22 is communicatively connected, by a fitting 23, with a passage 24 formed in the body portion 16' of the carburetor and leading downwardly, at an inclination, as shown in Fig. 2, to and opening into the fuel mixture passage 17. The carburetor body portion 16' is also provided with a substantially horizontal bore 25 which intersects the passage 24 and in which is journalled a throttle valve shaft 26 having a throttle blade 27 mounted thereon and disposed in the fuel mixture passage 17 at a location above the outlet end portion 28 of the passage 24. That portion of the throttle valve shaft 26 which extends through the common section of the passage 24 and bore 25 is so notched, as illustrated at 28' in Figs. 3 and 4, as to serve as a valve member for controlling the flow of air and withdrawn crank case diluents from the crank case 11. The throttle valve shaft 26 has an external end portion on which is fixed a lever 29 that is operatively connected with an accelerator rod or other suitable control rod 30. The throttle valve

27 and the valve section 28' of the shaft 26 are simultaneously operated by the lever 29 and rod 30 during controlling of the speed of operation of the engine.

5 28 The valve section 28' of the throttle valve 26 is so constructed and arranged as to accommodate only a minimum flow of air and crank case diluents from the crank case when the throttle valve is positioned to establish idling operation 10 of the engine. When the throttle valve is moved from its idling position, illustrated in Fig. 3, to its substantially full open position shown in Fig. 4, the valve section 28' of the throttle shaft 26 is turned to the position shown in Fig. 4 at 15 which it accommodates the maximum flow of air and crank case diluents from the crank case to the fuel induction system. The amount of air and crank case diluents withdrawn from the crank case is gradually increased as the throttle is moved 20 from its idling position to its wide open position.

Withdrawing of air and crank case diluents from the crank case is induced by the normal carburetor suction, as well as by the ejector effect 25 which results from the inclination of the passage 24, shown in Fig. 2, with respect to the axis of the fuel mixture passage 17 at the location where the passage 24 opens into the passage 17.

During operation of the engine at idling speed, 30 the valve provided by the section 28' of the throttle shaft 26 permits the withdrawal of sufficient air and crank case diluents from the crank case of the engine to prevent the accumulation of such diluents therein. During such operation of the engine the throttle valve is substantially closed and a relatively high vacuum is available for the promotion of an air circulation through the crank case. As the throttle valve is opened to increase the engine speed, the vacuum is somewhat reduced and at high speed operation of the engine there is an additional amount of fuel flowing by the piston into the crank case. The opening of the valve simultaneously with opening of the throttle compensates for this additional 45 blow-by gas as well as for reductions in the vacuum of the fuel induction system. By virtue of this construction, ample circulation of air through the crank case and withdrawal of diluents therefrom is provided during idling operation 50 and excessive removal of lubricant vapor from the crank case is avoided while during high speed operation provision is made to accommodate the withdrawal of the blow-by gases from the crank case which are incident to fast operation of the engine.

In order to prevent disturbing of a predetermined fuel mixture ratio of the fuel mixture supplied to the engine for starting purposes, a valve 31 may be provided in the conduit 22 by 60 which the ventilating system may be rendered inoperative during the starting operation. The valve 31 is preferably controlled by a solenoid 32 which is electrically connected in series with the switch 33 of the engine starting system. When the switch 33 of the starting system is closed in a conventional manner, by depression, for example, of a starter pedal 34, the valve 33 is closed so as to prevent the application of carburetor suction on the crank case. After the engine is started

and the pedal 34 is released, the valve 31 is returned to its open position, preferably by a spring (not shown) in accordance with the usual practice in solenoid valve operation. This valve action is beneficial in many installations but is not essential in all cases. 5

Although but one specific embodiment of the invention is herein shown and described, it will be understood that various changes in the size, shape and arrangement of parts may be made 10 without departing from the spirit of my invention.

What I claim is:

1. In an internal combustion engine including a crank case having ventilating air inlet and outlet openings and having fuel induction and engine starting systems; a control for said fuel induction system, a crank case ventilating system including means communicating with said outlet opening and with said fuel induction system at a location in the latter of subatmospheric pressure 20 for inducing the flow of a current of air through said crank case and for withdrawing diluents therefrom, variable valve mechanism in said means for controlling the quantity of air and diluents withdrawn from said crank case, apparatus for regulating said valve mechanism in accordance with the operation of said fuel induction system control, and mechanism responsive to actuation of said engine starting system for discontinuing the flow of air and fuel vapor 30 through said means when said starting system is operative. 25

2. In an internal combustion engine including a crank case having ventilating air inlet and outlet openings and having fuel induction and electric engine starting systems; a control for said fuel induction system, a crank case ventilating system including means communicating with said outlet opening and with said fuel induction system at a location in the latter of subatmospheric pressure 40 for inducing the flow of a current of air through said crank case and for withdrawing diluents therefrom, variable valve mechanism in said means for controlling the quantity of air and diluents withdrawn from said crank case, apparatus for regulating said valve mechanism in accordance with the operation of said fuel induction system control, and valve mechanism in said means including a solenoid actuating member 45 electrically connected with said engine starting system and energizable simultaneously therewith for discontinuing the flow of air and crank case diluents through said means during engine starting operations. 50

3. In an internal combustion engine including a crank case having ventilating air inlet and outlet openings and having fuel induction and engine starting systems; a crank case ventilating system including means communicating with said outlet opening and with said fuel induction system at a location in the latter of subatmospheric pressure for inducing the flow of a current of air through said crank case and for withdrawing diluents therefrom, and mechanism responsive to actuation of said engine starting system for discontinuing the flow of air and fuel vapor through said means when said starting system is operative. 60
